UNITED STATES PATENT OFFICE.

AARON ALLEN, OF PHILADELPHIA, PENNSYLVANIA.

DESIGN FOR A CUTTING-BLADE FOR WALL-PAPER-TRIMMING MACHINES.

SPECIFICATION forming part of Design No. 30,676, dated May 2, 1899.

Application filed March 15, 1899. Serial No. 709,215. Term of patent 14 years.

To all whom it may concern:

Be it known that I, AARON ALLEN, a citizen of the United States, residing at the city of Philadelphia, in the county of Philadelphia and State of Pennsylvania, have invented and produced a new and original Design for a Cutting-Blade for Wall-Paper-Trimming Machines, of which the following is a specification, reference being had to the accompanying drawings, forming part hereof, in which—

Figure 1 is a side elevational view of the back face of the cutting-blade for a wall-paper-trimming machine, showing the particular shape and configuration of the same of my design. Fig. 2 is a vertical central sectional view through the cutting-blade of Fig. 1, and Fig. 3 is a front elevational view of the front face of the cutting-blade.

The leading feature of my design consists in the peculiar outline or configuration of the blade A. As illustrated in the drawings, the blade in cross-section has a dish-shaped base a, and surrounding this base is a rim which is rounded both on the interior, as at b, and the exterior, as at d, at the points where it

merges into the base a. The interior of the rim is beveled, as at b', and the exterior of the rim is also beveled, as at c, the two bevels merging into an acute-angled edge b'', which is not parallel to the vertical axis of 30 the blade, but is at an acute angle thereto, so that the edge b'' flares outward and away from the periphery of the blade to form a cutting edge. The back e of the base of the blade is substantially flat and circular in outline, and 35 within the circular base a is arranged a central circular aperture or opening f.

Having thus described my invention, what I claim as new, and desire to secure by Letters Patent, is—

The design for a cutting-blade for wall-paper-trimming machines, as herein shown and described.

In testimony whereof I have hereunto set my signature in the presence of two subscribing witnesses.

AARON ALLEN.
